Middleee & Allyn.

UNITED STATES PATENT OFFICE.

EMMA W. DOUGHTY, OF CRESSKILL, NEW JERSEY, ASSIGNOR TO CHENEY BROTHERS,
OF SOUTH MANCHESTER, CONNECTICUT, A CORPORATION OF CONNECTICUT.

DESIGN FOR A TEXTILE FABRIC.

47,715.

Specification for Design.

Patented Aug. 17, 1915.

Application filed June 2, 1915. Serial No. 31,776. Term of patent 3½ years.

To all whom it may concern:

Be it known that I, EMMA W. DOUGHTY, a citizen of the United States, residing at Cresskill, Bergen county, New Jersey, have invented a new, original, and ornamental Design for Textile Fabrics, of which the following is a specification, reference being had to the accompanying drawing, forming a part thereof, in which I have shown in a single plan view the said design.

I claim—

The ornamental design for a textile fabric as shown.

EMMA W. DOUGHTY.

Witnesses:

R. C. MITCHELL,
FLORYME S. HADLEY.
